Attorney

UNITED STATES PATENT OFFICE.

WILLIAM D. CULWELL, OF AUBURN, NEBRASKA.

GATE.

SPECIFICATION forming part of Letters Patent No. 499,970, dated June 20, 1893.

Application filed April 13, 1893. Serial No. 470,217. (No model.)

To all whom it may concern:

Be it known that I, WILLIAM D. CULWELL, a citizen of the United States of America, residing at Auburn, in the county of Nemaha and State of Nebraska, have invented certain new and useful Improvements in Gates; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a swinging gate with latch mechanism which is so constructed that the weight of the gate will co-act with the latches to hold them in engagement with the catches on the gate post, the latch mechanism also serving to elevate the free end of the gate as it is swung open so that the gate will automatically close.

The invention consists in the construction and combination of the parts, as will be hereinafter fully set forth, and particularly pointed out in the claims.

In the accompanying drawings, forming part of this specification, Figure 1 is a perspective view of a gate constructed in accordance with my invention. Fig. 2 is a view of the rear end of the gate, showing its connection with the gate-post, and Fig. 3 is a vertical sectional view through the rear end of the gate.

A and A' designate the gate-posts, the post A' having attached thereto catches $\alpha\alpha$ the upper surfaces of which are inclined toward the central notch. At the lower end of the post A is located a base-piece b , and at the upper end is secured a projecting plate b' the outer end of which is provided with perforations c , and between said perforations is an aperture d which receives a pin projecting upwardly from a fixture D, said fixture having side members which embrace the gate and permit the same to slide therein to assume the position shown in Fig. 2. The lower end of the gate has attached thereto a strap e which extends under the gate and is provided with an aperture e' to receive a pivot-pin e'' projecting from the base-piece b . By this means the gate is pivoted to the post to have both a swinging and a tilting movement.

E and E' designate the latches, the lower latch, E', being pivoted between the short vertical battens $f f$, while the upper latch, E, is pivoted between the diagonal braces $f' f'$, so that the pivots of the latches will be out of a vertical line. The upper latch is connected to the lower latch by a connection g , which may be either a wire loop or a bar having bent ends, and it will be noted that the upper latch is extended to provide a hand-grasping portion. The lower latch has connected thereto flexible connections $h h$ which extend therefrom around suitable guides $i i$ up to and through guides k to a ring attached to the ends of short chains $l l$, said chains being connected to the plate, b' by means of the perforations $c c$ therein.

In operation, when it is desired to open the gate the operator depresses the projecting end of the latch E and the end which engages with the catch will move the lower latch with it and raise the gate by means of the flexible connections $h h$. The latches being free the gate can be swung open, and as it swings one of the flexible connections h will be tightened while the other becomes slack, thus tilting the free end of the gate so that it will close automatically. When the gate is closed the weight is partially supported by the connections $h h$ so as to hold the latches in positive engagement with the catches.

The guide k is preferably made of a single piece, comprising a loop which embraces the upper rail of the gate and an eye at each end through which the flexible connections pass, and should the flexible connections become slack they can be readily tightened by changing the position of the guide upon the rail.

Having thus described my invention, what I claim as new, and desire to secure by Letters Patent, is—

1. A gate pivoted to a support at its lower end and held in sliding engagement with a fixture at the upper portion of a supporting post, a plate secured to the upper end of the supporting post and projecting therefrom, flexible connections $l l$ attached to the plate, and a flexible connection h connected to the flexible connections $l l$ and extending therefrom over suitable guides to a pivoted latch, said latch being adapted to engage with a

catch attached to the gate post, substantially as shown, and for the purpose set forth.

2. In combination with a swinging gate movably connected to the supporting post at its lower end, a plate or projection secured to the upper end of the post, a fixture pivoted thereto and provided with depending members which embrace the upper rail of the gate and permit a sliding movement of the same in the fixture, flexible connections attached to the projecting ends of the plate, said flexible connections being brought together to engage with flexible connections *h h* which are attached to the latch bar, substantially as shown, and for the purpose set forth.
3. In a gate constructed substantially as

shown, the combination, of the pivoted latches E and E' connected to each other at the ends which engage with the catches, flexible connections leading from one latch to a plate extending from the supporting post, and a fixture pivoted to said plate in which the upper end of the gate slides when swung upon its pivot, substantially as shown, and for the purpose set forth.

In testimony whereof I affix my signature in presence of two witnesses.

WILLIAM D. CULWELL.
